UNITED STATES PATENT OFFICE.

FREDERICK E. ARASON, OF EDINBURG, NORTH DAKOTA, ASSIGNOR TO A. SCHRADER'S SON, INCORPORATED, OF BROOKLYN, NEW YORK, A CORPORATION OF NEW YORK.

DUST-CAP.

1,370,261.

Specification of Letters Patent.

Patented Mar. 1, 1921.

Application filed June 12, 1919. Serial No. 303,731.

To all whom it may concern:

Be it known that I, FREDERICK E. ARASON, a citizen of the United States of America, residing in Edinburg, county of Walsh and 5 State of North Dakota, have invented certain new and useful Improvements in Dust-Caps, of which the following is a specification.

The invention relates to dust caps for automobile tire valves or the like, and aims to provide improvements therein.

The present invention provides a dust cap of simple construction, and capable of being applied over, and removed from, the 15 portion of the valve casing which extends beyond the inner face of the rim, with quickness and a minimum of effort.

Other features of improvement will be hereinafter pointed out.

20 An embodiment of the invention is illustrated in the accompanying drawings, wherein—

Figure 1 is a vertical sectional view illustrating said embodiment of dust cap applied to a tire valve casing.

Fig. 2 is a view in elevation of the dust cap.

Fig. 3 is a view, partly in section and partly in elevation, of the dust cap in position for placement over, or removal from the projecting end of the valve casing.

Fig. 4 is a sectional view on line IV—IV of Fig. 3.

Fig. 5 shows in vertical cross-section a 35 slightly different embodiment of the invention.

Referring to said drawings, numeral 1 designates a tire valve of the well-known Schrader type, comprising an exteriorly 40 screw-threaded casing 2, and a foot 3. There is also preferably provided a rim nut 4 screwing upon the casing 2 and holding the casing firmly connected to the rim 5 through which the casing passes.

45 The projecting end of the valve casing is usually covered with a dust cap.

The present dust cap comprises longitudinal sections or shells 6 and 7, preferably halves, and these shells or halves are pivotally connected, as indicated at 8. The 50 contour of the collective shells or halves is preferably round, though it may be of other shape.

The base portions of the shell or halves

6 and 7 are provided with engaging means 55 10 adapted to engage the body of the valve casing or other part to which the dust cap is attached, in order to hold it in place over the projecting end of the valve casing. These engaging means 10 are conveniently 60 screw-threads adapted to engage or mesh with the threads on the exterior of the valve casing 2.

The pivotal axis of the connected halves or shells 6 and 7 is preferably between the 65 base portions and the upper ends of the shells, whereby the upper ends of the shells or halves may be pressed together and the opposite ends or base portions spread, or moved, apart, thereby carrying the engaging 70 means 10 on the base portions of the shells 6 and 7 out of engagement with the threads on the casing 2, or other part, as indicated in Fig. 4. Suitable means are provided for holding the engaging means 10 75 of the dust cap in engagement with the valve casing or other part to which the dust cap is to be attached. This means may conveniently be a spring 12 adapted to resiliently press the base ends of the shells or halves 80 6 and 7 together. The spring 12 is conveniently a coiled compression spring located in the upper part of the interior of the dust cap, and bearing against opposite parts of the shells or halves 6 and 7. Indentations 14 may be provided for holding the spring in place.

When the base portions of the shells 6 and 7 are removed or spread apart, as indicated in Figs. 3 and 4, the dust cap may 90 be readily and quickly moved the length of the projecting portion of the valve casing, and carried to, or removed from, its position over the projecting end of the valve casing.

95 After the valve cap has been placed in position over the projecting end of the valve casing, as described above, in order to fasten it in such position, it is simply necessary to bring the base portions of the halves or shells 6 and 7 together around the valve casing 2, or other part, in such manner that the engaging means or threads on the parts 6 and 7 engage the threads on the valve casing 2, or other part. If in this position the 100 base of the dust cap is not firmly seated against the rim or rim nut, it is simply necessary to give the cap a turn, or partial

turn, until the base is firmly seated against the rim or rim nut.

From the foregoing it will be seen that in order to place the dust cap over the projecting end of the valve casing, it is not necessary to turn it the number of times corresponding to the number of threads above the face of the rim, as with some dust caps, but the dust cap may be quickly and easily placed in position over the projecting end of the dust cap by directly moving it the length of said projecting end of the valve casing, which is permitted by the separation or spreading of the base portions of the dust cap, as indicated in Figs. 3 and 4, and when in such position the dust cap may be secured by simply bringing together the spread base portions of the dust cap around the valve stem or other part, and giving the valve cap a turn or partial turn, if necessary.

The meeting faces of the halves or shells 6 and 7 below the pivotal axis 8 preferably abut, edge to edge. The meeting edges of 25 the halves or shells 6 and 7 above the pivotal axis 8 preferably slightly overlap, and the upper ends or portions of the shells or halves are formed in a manner to allow partial telescoping, or the reception one within 30 the other of the upper portions of the shells.

Where the dust cap is round, or substantially round, this may be accomplished conveniently by providing one of the shells with a recess 15, and providing the other shell 35 with a marginal indented portion 16. However, instead of forming the recess in one and the marginal indentation in the other, the reception of the upper end of one in the upper end of the other shell may be provided 40 for solely by recessing one of the parts, as indicated at 15' in Fig. 5.

The mode of use of the invention will be apparent from the foregoing description.

The inventive ideas herein set forth may 45 be otherwise embodied than as herein specifically illustrated and described.

What I claim is:—

1. A dust cap comprising parts divided longitudinally of the dust cap and pivotally 50 connected intermediate the base and top thereof, and means on said parts for engaging a valve casing or the like for holding the dust cap in place, said engaging means being brought into and out of engaging position by pressing inwardly upon the upper

ends of said pivoted parts so as to move said parts around the pivotal connection.

2. A dust cap comprising parts divided longitudinally of the dust cap and pivotally connected, and means on said parts for engaging a valve casing or the like for holding the dust cap in place, said engaging means being brought into and out of engaging position by movement of said parts around the pivotal connection, one of said parts, at the 65 outer end, being provided with a recess wherein the outer end of another of said parts may enter or partially telescope when the parts are pressed together.

3. A dust cap comprising parts divided 70 longitudinally of the dust cap and pivotally connected, a spring normally pressing said parts together, and means on said parts for engaging a valve casing or the like for holding the dust cap in place, said engaging 75 means being brought into and out of engaging position by movement of said parts around the pivotal connection.

4. A dust cap comprising two metal longitudinal halves or shells, pivotally connected intermediate the base and top thereof, said halves having screw-thread engaging means thereon adapted to engage screw-threads on a valve casing or the like, one of said halves, at its upper end being provided 85 with a recess for receiving the other half when the two upper ends are pressed together, and a spring adapted to normally press the base ends of said halves together in a manner to bring the thread-engaging 90 means thereon into engagement with threads on a valve casing or the like, said thread-engaging means being releasable from engagement with said threads by pressing upon the upper ends of said halves against 95 the pressure of said spring.

5. A dust cap comprising two metal longitudinal halves or shells, pivotally connected intermediate the base and top thereof, said halves having screw-thread engaging means thereon adapted to engage screw-threads on a valve casing or the like, one of 100 said halves, at its upper end being provided with a recess for receiving the other half when the two upper ends are pressed together, and the other half being provided 105 with a corresponding marginal indentation.

In witness whereof, I have hereunto signed my name.

FREDERICK E. ARASON.
